UNITED STATES PATENT OFFICE.

ALVUS ELWOOD McKNIGHT, OF CHICAGO, ILLINOIS.

WARMING DEVICE.

No. 799,661.

Specification of Letters Patent.

Patented Sept. 19, 1905.

Application filed October 24, 1904. Serial No. 229,795.

To all whom it may concern:

Be it known that I, ALVUS ELWOOD McKNIGHT, a citizen of the United States, residing at Chicago, in the county of Cook and 5 State of Illinois, have invented a new and useful Warming Device, of which the following is a specification.

This invention relates to devices employed in connection with cooking or heating apparatus for warming food products and for like purposes, and has for its object to provide a simply-constructed and efficient device which may be employed in connection with any of the various forms of cooking and heating apparatus, more particularly the numerous forms and styles of oil, gas, or vapor stoves in general use.

With these and other objects in view, which will appear as the nature of the invention is better understood, the same consists in certain novel features of construction, as herein-after fully described and claimed.

In the accompanying drawings, forming a part of this specification, and in which corresponding parts are denoted by like designating characters, is illustrated the preferred form of the embodiment of the invention capable of carrying the same into practical operation, it being understood that the invention 25 is not necessarily limited thereto, as various changes in the shape, proportions, and general assemblage of the parts may be resorted to without departing from the principle of the invention or sacrificing any of the advantages.

In the drawings thus employed, Figure 1 is a side view of a conventional gas-stove with the improved device in vertical section disposed thereon. Fig. 2 is an inverted perspective view of the improved device.

The improved device comprises a drum or shell 10, open at one end and with the other end provided with an outwardly-flaring rim 11, provided with a plurality of spaced vent-apertures 12 and connected at its free end to a platform 13, the platform being thus supported by the adjacent end of the drum 10 and spaced therefrom. Attached to the inner walls of the drum 10 is a brace member 14, 45 extending in advance of the end of the drum and bearing against the inner surface of the

platform to support the same and prevent its depression when in use. The open end of the drum is designed to be placed over one of the burners of a vapor, gas, or oil stove or upon 55 the upper surface of a cook-stove or some forms of heating-stoves, but, as before stated, is more particularly designed for use upon vapor, gas, or oil cooking-stoves, and for the purpose of illustration is shown applied to a 60 conventional form of a gas-stove in which the base or frame is represented at 15 and the burners at 16 17, with the drum 10 in position over one of the burners. The drum, it will be obvious, occupies comparatively little space 65 and is long enough to cause the flaring portion 11 to project above any cooking utensils which may be for the time being in use upon the other burner. The presence of the device, therefore, does not seriously interfere 70 with the use of the remaining burners on the stove. The platform 13 thus provides an extended surface for the reception of dishes of food of various kinds which it is desired to keep warm and will be thus maintained at a 75 uniform temperature from the heat rising from the burner within the shell or drum.

The device may be of any desired size and of any required material and the platform 13 of any required shape, irrespective of the shape 80 of the drum 10, so that the area of the platform may be increased or decreased, as required.

Having thus described the invention, what is claimed is—

In a device of the class described, a cylindrical drum, a brace member connected with opposite sides of the drum and supported above the latter, an upwardly and outwardly flaring flange provided with vent-apertures near its 90 upper portion, connected at its inner edge with the upper end of the drum and terminating at its outer edge on a level with the brace member, and a plate or platform supported upon said flange and brace member. 95

In testimony that I claim the foregoing as my own I have hereto affixed my signature in the presence of two witnesses.

ALVUS ELWOOD McKNIGHT.
